UNITED STATES PATENT OFFICE.

JOSEPH KISSICK, JR., OF NEW YORK, N. Y., AND CHARLES DE VED, OF PHILADELPHIA, PENNSYLVANIA, ASSIGNEES TO FREDERICK W. LINAKER, OF DUBOIS, PENNSYLVANIA.

TUBE-CLEANER FOR BOILERS.

1,318,294.

Specification of Letters Patent.

Patented Oct. 7, 1919.

Application filed February 28, 1917. Serial No. 151,521.

To all whom it may concern:

Be it known that we, JOSEPH KISSICK, Jr., residing in the borough of Manhattan, city, county, and State of New York, and 5 CHARLES DE VED, residing in the city and county of Philadelphia, in the State of Pennsylvania, both citizens of the United States of America, have jointly invented certain new and useful Improvements in Tube-10 Cleaners for Boilers, of which the following is a specification.

This invention relates to tube cleaners for boilers, especially boilers of the water tube type having staggered rows of tubes, and 15 aims to provide improvements therein.

Revolving or oscillating jets of steam are used for blowing down the diagonal space between rows of boiler tubes, for the purpose of blowing off the soot and ash deposit 20 which settles upon the tubes.

The present invention relates to this type of cleaners, and provides a simple and efficient construction whereby the jet is rendered effective throughout its revolution or 25 oscillation in the direction of the diagonal between the tubes, the invention comprising deflecting means which maintain the jets substantially in the mid plane of the diagonal space between the rows of tubes, sub-30 stantially throughout the part of the movement of the jet in the direction of the bank of tubes.

It is important to maintain the axis of the jet in the mid plane of the interval between 35 the rows of tubes, inasmuch as otherwise the jet is too much broken up, in whole or in part, thereby not reaching tubes, or portions of tubes, in a lower part of the bank, and also is of insufficient intensity to carry off 40 the soot which is blown off of the tubes.

Moreover, as the atmosphere in which the cleaners work is quite hot and contains acid, 45 gases or fumes, it is essential that the construction be of maximum simplicity and have a minimum of moving parts. Moreover, the impingement of jets on the tubes has an appreciable wearing action thereon.

Two embodiments of the invention are illustrated in the accompanying drawings.

50 In said drawings,—

Figure 1 is a transverse sectional view of a boiler showing one embodiment of the invention applied thereto;

Fig. 2 is a detail view of the embodiment 55 of the invention shown in Fig. 1;

Figs. 3 and 4 are respectively a side elevation and a top plan view of the construction shown in Fig. 2;

Fig. 5 is a view similar to Fig. 1, showing a second embodiment of the invention; 60

Fig. 6 is a detail view of the embodiment shown in Fig. 5, the parts being shown in section;

Figs. 7 and 8 are side elevation and top plan views respectively of the construction 65 shown in Fig. 6.

Referring first to the embodiment shown in Figs. 1 to 4 inclusive, the numeral 1 designates a series of boiler tubes arranged in diagonal rows; 2 designates a steam pipe 70 adapted to be rotated or oscillated at suitable times, and by suitable means through a sprocket wheel 3 or the like. Upon the pipe 2 is a series of nozzles 4 adapted to direct jets of steam down the interval between the 75 rows of tubes, the cleaning being done by diverging portions of the jet striking against the tops and sides of the tubes and blowing off the soot or ash thereon. There is also a secondary cleaning action of the jet due 80 to the deflection of the diverging portions thereof from one tube to another.

The nozzles 4 have their axes substantially parallel or coincident with the mid plane of the diagonal interval between the 85 tubes, when the nozzle is directed downwardly at one (or two) point. Referring to Fig. 2, it will be seen that the axis 7 generates a conoidal surface z , or a portion of a conoidal surface, as it revolves or oscillates. The surface of the cone is hence only parallel or coincident with the mid plane of the diagonal interval between the tubes at one (or two) point. At other points of its movement the jet is blowing either more 90 toward the tubes on one side of the mid plane of the interval, or toward the tubes on the other side. Sufficient movement will bring the jets to a point where the tubes will entirely or largely deflect the jet from 95 the diagonal interval between the tubes. Hence it is possible for the jets to blow straight down the interval between the tubes for only a very limited part of its movement. The efficiency of the jet is hence 100 much below its maximum.

In order to maintain the axis of the jet coincident or parallel to the mid plane of the interval between the tubes during the time that the nozzles are blowing in the direction 110

of the tubes, means are provided for this purpose. The means preferably comprise deflectors 8 having suitably warped or curved surfaces 9 to deflect or correct the jet, so that it will blow with its axis substantially parallel or coincident with the mid plane of the interval between the tubes, in all positions of the nozzle where it blows in the direction of the bank of tubes. In the construction illustrated the surface between the curved lines x and y is a curved surface formed by joining the end points of an infinite number of radiating parallels to the revolving axis of the jet (having their locus in the line x) to the end points of an infinite number of radiating lines running parallel to the mid plane of the diagonal interval (having their locus in the line y).

The spacing of the jets and deflectors is preferably such as to give the desired cleaning action. One may be placed in conjunction with each tube row or interval, or in conjunction with alternate rows or intervals, or otherwise. As here shown the deflectors are placed in conjunction with alternate tube rows or intervals, and the jets or nozzles are in pairs adapted to blow down intersecting diagonal intervals.

Conveniently, also, the deflecting surfaces 9 may be formed upon a saddle 11 which straddles a pipe, which saddle may, also conveniently, have bearings 12 thereon for supporting the tube 2 through which the steam is conveyed to the nozzles 4.

Referring to the embodiment shown in Figs. 5 to 8 inclusive, the numeral 1 indicates, as before, rows of boiler tubes; the numeral 2 a steam pipe, and 4' nozzles adapted to direct jets of steam into the interval between the rows of tubes. The axes 7' of the nozzles, in this embodiment, revolve in a circular plane, which circular plane is at an angle to the mid plane between the diagonal interval between the rows of tubes. For directing and maintaining the jets in the mid plane of the diagonal interval, suitable deflecting means 8' are provided, these deflecting means being provided with suitably concaved surfaces 9', the curvature decreasing from the middle toward the side portions v , v . The action of the surfaces 9' will be to deflect the jet into the diagonal interval between the rows of tubes, throughout the portion of the revolution of the jets where the jets blow in the direction of the tubes. The diverging portions of the jet and the deflections of these diverged portions by the tubes, effect the cleaning off of the soot, etc., deposited on the tubes.

The deflectors and jets may be so disposed with relation to the rows of tubes as to give the desired cleaning effect. As here shown, the deflectors are shown as formed upon a saddle 11' carried by a tube in every

other row. The construction is also shown as arranged to blow down intersecting diagonal intervals, which is a preferable arrangement. The saddles 11' may have bearings 12' thereon for the rotating steam pipe 2. 70

In certain types of boilers, the diagonal rows of tubes are not strictly in a straight line, but are slightly staggered. In this case it is desirable not to have the axes of the jets entirely symmetrical with respect to the vertical plane w of the tubes. The axis of the jet upon one side (as here shown, upon the left-hand side of Fig. 6) is nearer its plane of symmetry than the axis of the jet upon the other side (the right-hand side of Fig. 6) is to its plane of symmetry. The effect of this arrangement is to diminish the deflecting action of the immediately-adjacent tubes.

While we have illustrated and described two embodiments of the invention, the invention is not to be understood to be limited thereto, as the inventive ideas are capable of more various mechanical expressions.

What is claimed is:—

1. A boiler-tube cleaner, comprising jet-forming means for directing a rotatable jet of steam toward a diagonal interval between rows of boiler tubes, and means for deflecting the jet to retain it in the diagonal interval between the rows of tubes, said deflecting means comprising a concaved curved surface. 90

2. A boiler-tube cleaner, comprising jet-forming means for directing a rotatable jet of steam toward a diagonal interval between rows of boiler tubes, and means for deflecting the jet to retain it in the diagonal interval between the rows of tubes, said deflecting means comprising a differentially concaved curved surface. 95

3. A boiler-tube cleaner, comprising jet-forming means for directing a rotatable jet of steam toward a diagonal interval between rows of boiler tubes, and means for deflecting the jet to retain it in the diagonal interval between the rows of tubes, said deflecting means comprising a pair of concaved curved surfaces, said surfaces being adapted to differently modify the jets impacting thereon. 110

4. A boiler-tube cleaner, comprising jet-forming means for directing a rotatable jet of steam toward a diagonal interval between rows of boiler tubes, and means for deflecting the jet to retain it in the diagonal interval between the rows of tubes, said jet-deflecting means comprising a concaved surface and a nozzle whose axis generates a plane surface intersecting the concaved surface. 120

5. A boiler-tube cleaner, comprising a steam-pipe capable of rotary movement, jet-forming nozzles thereon for directing a jet of steam toward the rows of boiler tubes, a 130

bearing for said rotary steam-pipe, said bearing having a concaved curved surface for deflecting the jet to retain it in the diagonal interval between the rows of tubes.

- 5 6. In a soot cleaner for water tube boilers, the combination of a revolvably mounted cleaning fluid distributing pipe having radial discharge jets, means for supporting the pipe adjacent the boiler tubes, and means
10 for protecting the tubes adjacent the cleaning pipe and for causing the jets issuing radially therefrom to travel in oblique paths through the boiler tubes, said last named means including a concaved face directly
15 contacted by the cleaning fluid issuing from said pipe.

7. In a soot cleaner for water tube boilers, the combination of a revolvably mounted

cleaning fluid distributing pipe having radial discharge jets, means for supporting 20 the pipe adjacent the boiler tubes, and means for protecting the tubes in line with the discharge jets and for causing the jets issuing radially therefrom to travel in oblique paths through the boiler tubes, said 25 last named means including a concaved surface curved on an arc concentric with the distributing pipe.

In witness whereof, we have hereunto signed our names in the presence of two 30 subscribing witnesses.

JOSEPH KISSICK, JR.
CHARLES DE VED.
